UNITED STATES PATENT OFFICE.

GEORGE WILKINSON, OF PROVIDENCE, RHODE ISLAND, ASSIGNOR TO THE
GORHAM MANUFACTURING COMPANY, OF SAME PLACE.

DESIGN FOR A SPOON.

SPECIFICATION forming part of Design No. 21,603, dated June 7, 1892.

Application filed May 8, 1892. Serial No. 431,724. Term of patent 7 years.

To all whom it may concern:

Be it known that I, GEORGE WILKINSON, a citizen of the United States, residing at Providence, in the county of Providence and State of Rhode Island, have invented and produced a new and original Design For Spoons, of which the following is a specification, reference being had to the accompanying drawing, forming part thereof.

- 10 The drawing is a view of a spoon, illustrating my new design. The leading features of my design for spoons consist in the narrow neck of the handle gradually increasing in width and forming alternating enlargements and contractions toward the upper portion of the handle, and the contraction of the upper end, relieved by rounded projections, together with the surface ornamentation, consisting of a foliated 15 ornament, having its base located at the point of juncture of the handle with the bowl, extending a short distance along the handle, a transversely-scored rib extending along the central portion of the neck a cluster of beadings 20 extending from the upper end of the rib and having rounded ends slightly spreading on the gradually-widening portion of the neck, an outwardly and slightly curved beading extending on each side of said cluster and ending 25 in a small convex ornament, scrolled beadings forming a border for the first enlargement, the following contraction and next enlargement extending in lines practically parallel with the outline and at a small distance 30 therefrom and broken by inwardly-projecting scrolls at the lower portion of the contraction, the upper ends of these beadings being scrolled inward, a short curved beading on the upper end, a wild flower, with foliage, represented below said short beading, and a view 35 showing white men habited in costumes of the seventeenth century, treating with an Indian who is seated on the ground against a 40 buffalo-robe, represented on the surface of the handle.

45 Number 2 in the drawing indicates the bowl of a spoon, and 3 the handle of the same. The interior surface of the bowl is ornamented by a supposed bird's-eye view of a portion of an 50 exhibition ground. The portion of the han-

dle 3 nearest the bowl forms a narrow neck, which gradually widens to 4 4, thence curves slightly inward to 5 5, then slightly outward and inward to 6 6, now curving slightly outward and extending upward for a short distance in lines almost parallel, and then curving outward to 7 7 and inward to meet the slight projections 8 8, which are joined across the top of the handle by the curved line 9. The foliated ornament 10 has its base located near 60 the point of juncture between the bowl 2 and handle 3 and extends for a short distance up the neck of the handle, ornamenting the lower portion of the rib 11, this rib being transversely scored by lines which, from being indistinct on the lower portion of the rib, become more prominent toward the upper end of the rib, and above this rib 11 extends the cluster 12 of longitudinal beadings, the upper 65 ends of which are rounded and are slightly separated. A border-bead 13 extends on each side of the cluster 12, following the outline of the handle and ending in the small convex projection 14, and above these the beadings 15 are scrolled inward and then outward and 70 upward, following the general outline of this portion of the handle. These beadings are crossed by the inwardly-curved scrolls 16 and end in the scrolls 17, and around the upper end of the handle is the curved beading 18. 75 Between the scrolls 17 is traced a representation of a wild flower 19, with foliage, having stems extending toward the projections 8. Above the cluster 12 and between the beadings 13 is represented a view of a grassy field, 80 with wigwams in the background, while above this and between the beadings 15 the view is continued, and in the foreground are the standing figures of two men, habited in garments of the seventeenth century, in earnest 85 conference with an Indian, who is seated on the ground before a buffalo-robe.

What I claim is—

The design for a spoon, as herein shown and described.

GEORGE WILKINSON.
